UNITED STATES PATENT OFFICE.

HERMAN G. PAPE, OF BUFFALO, NEW YORK.

DESIGN FOR AN ACOUSTIC EARPIECE.

42,295.

Specification for Design.

Patented Mar. 12, 1912.

Application filed December 28, 1908. Serial No. 469,735. Term of patent 14 years.

To all whom it may concern:

Be it known that I, HERMAN G. PAPE, a citizen of the United States, residing at Buffalo, in the county of Erie and State of New York, have invented a new, original, and ornamental Design for an Acoustic Earpiece, of which the following is a specification.

Reference is had to the accompanying drawing, in which:—

Figure 1 is a side elevation of an acoustic ear piece, showing my new and original design. Fig. 2 is a front elevation of the same. Fig. 3 is a rear elevation of the acoustic ear piece.

As shown in the accompanying drawing, the leading features of my design reside in the circular receiver 1, having reversely curved front and rear faces 2 and 3; the annular series of radially arranged raised ribs 4 dividing the rear face of the receiver; and the smooth curved contrasting tapered stem 5, having inner and outer rings 6 and 7 of different diameters, the inner ring 6 encircling the stem at the rear or inner ends of the radial ribs.

The receiver consists of a relatively thin circular body portion, and the outer portion of its front face is convexly curved. The outer portion of the rear face is concavely curved, and the central portion is provided with a tapered enlargement 8, which merges into the stem 5. The ribs 4 have a substantially compound curve and extend from the rim to the central tapered portions 8. The stem curves rearwardly and laterally from the tapered portion 8, and its outer end extends in a plane in parallelism with the rim of the receiver.

I claim:—

The ornamental design for an acoustic ear piece, as shown and described.

In testimony, that I claim the foregoing as my own, I have hereto affixed my signature in the presence of two witnesses.

HERMAN G. PAPE.

Witnesses:

ERNST PRÜMERS,
GERTRUDE M. WELLES.
